UNITED STATES PATENT OFFICE

2,285,349

STEAM GENERATING APPARATUS

Antoni Muszynski, Southampton, Mass.

Application June 20, 1940, Serial No. 341,482

1 Claim. (Cl. 122—234)

My invention relates to improvements in steam generating apparatus and other types of water heaters and the principal objects of my invention are directed to the provision of a steam generating apparatus which is characterized principally by its simplicity in design and by its efficiency of operation.

In connection with pressing machines or the like, where steam is used, it is usually desired to produce the steam as economically and as efficiently as is possible and to that end, the novel construction of my invention is adapted.

With the foregoing and various other novel features and advantages and other objects of my invention as will become more apparent as the description proceeds, the invention consists in certain novel features of construction and in the combination and arrangement of parts as will be hereinafter more particularly pointed out in the claim hereunto annexed and more fully described and referred to in connection with the accompanying drawing wherein:

Fig. 1 is a side elevational view of a steam generating apparatus embodying the novel features of the invention; and

Figs. 2 and 3 are sectional plan views on the lines 2—2 and 3—3 respectively of Fig. 1.

Referring now to the drawing more in detail, wherein similar reference figures refer to like parts, and referring more particularly to the preferred form of my invention which has been selected for illustrative purposes, I have shown a base which is represented by 2. This base has side walls 4 which may consist of a refractory material which is sheathed with plates or layers of metal substantially as shown. A burner B is represented in dot-dash lines and this may be of any well-known form for delivering oil and air to the combustion chamber within the base 2.

A plate 6 on the upper side of the walls 4 has a central opening which is surrounded by a vertically disposed flange, substantially as shown. A ring 8 encircling the vertical flange and resting upon the plate member 6 has a plurality of inwardly extending supports 10 which are adapted for supporting a boiler 12. The boiler 12 may be of the tubular type and through its body the gases pass upwardly from the combustion chamber for purposes of heating the water contained therein.

Suitable pipes, such as 13, are associated with the boiler for conducting the condensate thereto and the steam therefrom.

A shell 14 surrounds the boiler and is suitably supported at its lower end in some suitable man-

ner as by the member 8. The said shell is spaced from the boiler as shown so as to provide an upwardly extending annular space which acts as a pressure relief means for the gases when the burner is in operation. An upper wall 16 of the shell preferably extends in a converging relation towards a flue or smoke pipe 18.

The supports 10 for the boiler and the ring 8 with which they are associated are so arranged that an annular space 11 is provided at the lower end of the boiler, as shown.

With the oil burner in operation, the hot gases pass upwardly through the boiler, for heating the water therein, to the stack 18 and also upwardly through the space 11 into and through the annular space and to the stack. The annular space or passageway acts to relieve excessive pressure when the burner is started to run.

The arrangement is such that a minimum of fuel is required for the volume of steam for a pressing machine or some like apparatus.

Not only is the water heated by the internal passage of hot flue gases but also the heat travels upwardly outside the boiler for transfer to the water therein.

If desired, the outer shell may be insulated so that the boiler retains heat and thereby contributes to the economy in operation.

Manifestly the specific details of construction may be considerably varied from those herein shown and described without involving any departure from the principle of the invention or sacrificing any of the advantages inherent therein. While I have described my invention in this specification in great detail and particularly with respect to the present preferred form thereof, it is not desired to be limited thereto since many changes and modifications may be made therein without departing from the spirit and scope of the invention.

The invention may be embodied in other specific forms without departing from the essential characteristics thereof. Hence, the present embodiments are therefore to be considered in all respects merely as being illustrative and not as being restrictive, the scope of the invention being indicated by the appended claim rather than by the foregoing description, and all modifications and variations as fall within the meaning and purview and range of equivalency of the appended claim are therefore intended to be embraced therein.

What it is desired to claim and secure by Letters Patent of the United States is:

Heating apparatus of the class described com-

prising in combination, a hollow base member formed to provide a combustion chamber having an open upper side, a plate member supported on top of said base member formed to have a vertically extending flange surrounding a central opening therein, an annular ring member having a vertically-disposed lower part encircling said flange and an upper part which flares inwardly and upwardly from the upper edge of said lower part above said flange and opening, a vertically-disposed tubular shell member having its lower marginal edge engaging said upper part of the ring member intermediate the upper and lower marginal edges thereof so as to be supported thereby, a boiler of less diameter than said shell

5 vertically disposed therewithin and providing a space therebetween, said boiler also being of such diameter that its perimeter is spaced from said upper marginal edge of the inwardly-flaring upper part of the ring member so as to provide a space therebetween which leads into the first-named space, and a plurality of separate supporting members extending inwardly towards one another from the inner side of said ring member below the upper marginal edge thereof, the lower side of said boiler being supported by said supporting members and the latter being spaced apart to provide passageways leading from the combustion chamber to said spaces.
